CLAIM

I claim the ornamental design for a straw lid, as shown and described.

DESCRIPTION

FIG. 1 is a Perspective view of a straw lid showing my new design;

FIG. 2 is a Front view of the straw lid as shown in FIG. 1; FIG. 3 is a Back view of the straw lid as shown in FIG. 1; FIG. 4 is a Right-side view of the straw lid as shown in FIG. 1;

FIG. 5 is a Left-side view of the straw lid as shown in FIG. 1;

FIG. 6 is a Top view of the straw lid as shown in FIG. 1; and, FIG. 7 is Bottom view of the straw lid as shown in FIG. 1. The broken lines are only for environmental purposes and form no part of the claimed design.
